CLAIM

The ornamental design for a gaming machine with card reader, as shown and described.

DESCRIPTION

FIG. 1 is a front perspective view of a gaming machine with card reader showing the new design;

FIG. 2 is a front view of the card reader shown in FIG. 1; FIG. 3 is a rear view of the card reader shown in FIG. 1; FIG. 4 is a right side view of the card reader shown in FIG. 1;

FIG. 5 is a left side view of the card reader shown in FIG. 1;

FIG. 6 is a top view of the card reader shown in FIG. 1; and, FIG. 7 is a bottom view of the card reader shown in FIG. 1. In these drawings, broken lines illustrate unclaimed environmental features and form no part of the claimed design.

1 Claim, 5 Drawing Sheets
